(57) **CLAIM**

The ornamental design for an inlet apparatus, as shown and described.

DESCRIPTION

FIG. 1 is a top-side isometric view of an inlet apparatus; FIG. 2 is an exploded top-side isometric view thereof scaled to 60% (percent);

FIG. 3 is a bottom-side isometric view thereof;

FIG. 4 is a first side view thereof;

FIG. 5 is a second side view thereof;

FIG. 6 is a third side view thereof;

FIG. 7 is a fourth side view thereof;

FIG. 8 is a top view thereof; and,

FIG. 9 is a bottom view thereof.

The evenly dashed broken lines shown in the drawings represent portions of the inlet apparatus that form no part of the claim. The dash-dot broken lines illustrate boundaries that form no part of the claim.
